UNITED STATES PATENT OFFICE.

JOHN P. CROSBY, OF BELMONT, NEW YORK.

LANTERN ATTACHMENT FOR BUGGIES.

SPECIFICATION forming part of Letters Patent No. 683,446, dated October 1, 1901.

Application filed February 23, 1901. Serial No. 48,560. (No model.)

To all whom it may concern:

Be it known that I, JOHN P. CROSBY, a citizen of the United States, residing at Belmont, in the county of Allegany and State of New

5 York, have invented new and useful Improvements in Lantern Attachments for Buggies, of which the following is a specification.

My invention relates to lantern-holders adapted to be secured to the under side of a 10 buggy or other vehicle body.

The object of the invention is to provide a device of the character named of simple and inexpensive construction which will securely support a lantern and may be readily opened 15 to release the lantern without the manipulation of thumb-screws or like clamping devices.

The construction of the improvement will be fully described hereinafter in connection 20 with the accompanying drawings, which form part of this specification, and its novel features will be defined in the appended claims.

In the drawings, Figure 1 is a side elevation of a lantern-holder embodying the invention secured to a vehicle-body with a lantern suspended therefrom. Fig. 2 is a front elevation of the same, and Fig. 3 is a view in perspective of the holder detached from the vehicle and with the lantern removed.

30 The reference-numeral 1 designates a plate or bracket formed adjacent to its ends with bolt-holes 2 and having depending from one side thereof a pair of arms 3, the lower ends of which are each formed with a semicircular recess 4. These arms 3 constitute stationary jaws adapted to coöperate with a pair of 35 movable jaws 5, depending from the ends of a plate 6. The inner sides of the jaws 5 are formed with semicircular recesses 7, which, together with the recesses 4 of the arms 3, 40 constitute circular seats for the frame 8 of a lantern.

The plate 6 is pivotally secured to the plate 1 by means of a lug 9, projecting centrally 45 from the upper side of the plate 6 and formed with an opening registering with the perforations of a pair of perforated ears 10, depending from the underside of the plate 1, a pivot-pin 11 connecting said lug and ears.

50 The plate 6 is formed with a handle extension 12, by means of which the jaws 5 are opened, and a coil-spring 13 is interposed be-

tween the plates 1 and 6 to normally hold the jaws 5 in closed position, the ends of the said spring being secured to the plates by any suitable means. 55

The plate 1 is secured to the under side of a buggy or other vehicle, preferably to the body 14 thereof, as shown in Figs. 1 and 2, by bolts 15. 60

The spring 13 forces the lower ends of the jaws 5 against the lower ends of the arms 3 and the projecting edge 16 of the plate 6 into contact with the upper portions of said arms 3, thus firmly securing the frame of the lantern in suspended position. By raising the handle extension 12 of the pivoted plate 6 the jaws 5 are opened to permit the removal of the lantern, as will be obvious from the drawings. The jaws are automatically retracted 70 when the handle 12 is released, and the quick and simple manipulation of the device to attach or detach the lantern is a characteristic feature of the improvement. 75

I claim—

1. A lantern-holder comprising a stationary plate adapted to be secured to a vehicle; arms depending from said plate recessed at their lower ends; a plate pivotally secured to the under side of the stationary plate; jaws 80 depending therefrom recessed at their lower ends; a handle projecting from said pivoted plate; and a spring interposed between said plate. 75

2. A lantern-holder comprising a stationary plate adapted to be secured to a vehicle; arms depending from said plate and recessed at their lower ends; a pair of perforated ears depending from the under surface of said plate; a plate located below said stationary 90 plate and having an upwardly-projecting lug fitting between said ears and having an opening registering with the perforations of the ears; a pivot-pin connecting the lug and ears; recessed jaws depending from the pivoted 95 plate; a handle projecting from said pivoted plate; and a spring interposed between said plates. 85

In testimony whereof I affix my signature in presence of two witnesses.

JOHN P. CROSBY.
